POST-MOUNTED LUMINAIRE

Anthony C. Donato, Westfield, N.J., assignor to Lightolier
Incorporated, Jersey City, N.J.

Filed Dec. 24, 1969, Ser. No. 20,639

Term of patent 14 years

Int. Cl. D26—03

U.S. Cl. D48—31

FIG. 1

FIG. 2

FIG. 3

FIG. 4

FIG. 1 is a perspective view of a post-mounted luminaire showing my new design;

FIG. 2 is an end view thereof;

FIG. 3 is a side elevational view thereof, and

FIG. 4 is a bottom plan view thereof.

I claim:

The ornamental design for a post-mounted luminaire, substantially as shown.
